UNITED STATES PATENT OFFICE.

ROBERT B. SWIFT, OF PORTLAND, MAINE.

LOCK-STRIKE.

No. 851,109.

Specification of Letters Patent.

Patented April 23, 1907.

Application filed February 16, 1906. Serial No. 301,390.

To all whom it may concern:

Be it known that I, ROBERT B. SWIFT, a citizen of the United States, and a resident of Portland, in the county of Cumberland and 5 State of Maine, have invented new and useful Improvements in Lock-Strikes, of which the following is a specification.

My invention relates to improvements in lock strikes and more particularly to the construction of the striker. It is designed to 10 make the latch bolt operate more easily when the door is being closed.

In the drawing herewith accompanying and making part of this application, Figure 1 15 is an elevation of my improved striker and Fig. 2 is a transverse sectional view of same taken on a line passing through the ball bearings.

Same letters of reference refer to like parts. 20 In said drawings A represents a keeper of usual construction having the slot B for the latch bolt, slot C for the lock bolt and striker D, the outer edge of the striker being beveled as seen at K. The striker is provided 25 with anti-friction balls E projecting slightly above the face thereof and held in place by a steel plate F secured to the back side of the striker, one of the balls being located near

the front edge of the striker. There may be an upper and lower series of balls.

30

The advantages of a plurality of balls in the same horizontal plane is that there is always anti-friction engagement of the parts from the time the latch bolt engages the striker until it passes into its slot in the 35 keeper.

Having thus described my invention and its use I claim:

1. The combination with a striker of a plurality of anti-friction balls mounted therein 40 and projecting above the surface thereof, one positioned near the front edge and the other spaced apart rearwardly therefrom.

2. The combination with a striker having a steel back plate of an anti-friction ball projecting above the surface of the striker and held in place by said steel plate.

In testimony whereof, I have signed my name to this specification in presence of two 45 subscribing witnesses this 13th day of February, 1906.

ROBERT B. SWIFT.

In presence of—

ELGIN C. VERRILL,
MARION RICHARDS.
